FUEL-PUMPING DEVICE

Application filed November 26, 1928. Serial No. 321,896.

The purpose of this invention is to provide an improved construction of a pumping device adapted for supplying fuel to an internal combustion engine adapted to be operated 5 from the engine cam shaft, and for that purpose comprising a casing adapted to be mounted on the engine crank case. It consists in the elements and features of construction shown and described as indicated 10 in the claims.

In the drawings:—

Figure 1 is a section in vertical plane through the pumping chambers and passages axial with respect to certain of them, showing 15 the structure mounted on the engine crank case.

Figure 2 is a section at the line 2—2 on Figure 1.

Figure 3 is a section at the line 3—3 on 20 Figure 1.

Figure 4 is a side elevation for showing two casing members adjusted to different relative positions.

The drawings show a conventional form of 25 pumping device as to the pumping chamber and inlet and discharge connections, including a fuel accumulating and sediment chamber on the intake line. As shown, the structure comprises two casing members, A and B, 30 which are formed with mated faces having mated recesses, *a* and *b*, respectively, and having clamped between them the pumping member consisting of a diaphragm, C, which constitutes a partition between the two recesses, *a* and *b*. The recess, *b*, constitutes the 35 pumping chamber which has fuel inlet passage, 20, and fuel discharge passage, 30. These passages are formed in an extension, *B*^x, of the casing member, B, said extension 40 projecting from an upper end portion of the member, B, and having at its under side a recess bounded by the flange, 23, for seating the upper end of a glass cup, D, which constitutes a fuel accumulating and sediment chamber, 45 said cup making water-tight junction at its upper end with the seat formed for it at the under side of said casing extension, *B*^x, the same being made liquid-tight by a suitable packing gasket, 24, and the cup being 50 clamped securely in position by familiar

means consisting of a yoke, 26, and a clamping cam lever, 27, seen at the lower end of the cup. The fuel intake passage leads from the pipe connection shown at 21, and opens downwardly as seen at 22 into the fuel accumulating and sediment chamber, D, from 55 which the liquid passes through a filter screen, D¹, and inside the screen obtains access at the lower end of a downwardly projecting tubular member, 24, leading to the inlet valve, 25, for which a seat is afforded by the upper end of the tubular member, 24. Said valve opens upwardly and is normally seated by gravity, but is provided with a spring, 26, for ensuring its seating under all 60 circumstances; said spring reacts at its upper end upon the lower end of a plug, 27, which closes a bore, 28, made though the casing top wall for admitting the tubular member, 24, and the valve, 25, for seating at 65 the upper end of said tubular member as described. This bore, 28, communicates with the horizontal bore, 20, above referred to as the inlet passage, leading to and discharging in the pumping chamber, *b*, at the upper part 70 thereof, said pumping chamber being positioned with a pumping diaphragm extending vertically and having its pumping movement horizontal.

The discharge passage, 30, leading horizontally from the extreme upper edge portion of the pumping chamber is deflected upwardly at 31 to the discharge valve, 32, for which a seat is provided by a bushing, 33, drive-fitted in the vertical bore, 34, of an upwardly protruding boss, 35, which projects from the extension, *B*^x, of the casing member, B, the same being threaded at the upper end to receive a closure plug, 37, which serves as a stop for the upper end of a spring, 39, by 80 which the safe seating of the valve, 32, is ensured.

The casing member, A, is formed for mounting the operating connections to the pumping member diaphragm, C, which derives its pumping movement from a cam, 40, on the engine cam shaft, 41, as herein-after described. The connections for operating the diaphragm comprise a plunger element, 50, which constitutes the immediate 100

means of actuating the diaphragm, said plunger being secured to the center of the diaphragm, clamping at the opposite sides thereof the diaphragm reinforcing or forming controlling disks, 51 and 52. A second plunger element comprising a plunger member, 55, is slidingly mounted in the casing at the end of the latter at which the casing is mounted on the engine crank case, into which said plunger member, 55, projects for co-operation with the cam, 40. The casing member, A, is formed as shown with the terminal portion, A¹, in which the plunger, 55, is mounted, offset from the portion, A², in which the plunger, 50, is mounted, laterally with respect to said plungers, and the two plungers which are thus offset laterally from each other, are connected with each other by a lever of the first class, 56, fulcrumed intermediate its ends in the casing at the portion, A³, thereof intermediate the two laterally offset portions, A¹ and A², of said casing. A spring, 60, is provided reacting at one end upon the diaphragm, C, and at the other end on the casing for yieldingly stressing the diaphragm in the direction of its feeding movement. A second spring, 61, is provided and coiled outside of the terminal portion, A¹, of the casing for reacting between the casing and the plunger member, 55, for yieldingly thrusting said member outwardly for the encounter of the cam, 40, with the head of said plunger member; a washer, 61^a, stopped against the inner side of the head, 52, of the plunger, serves for stopping the spring, 61, for its reaction upon the plunger member, 55. The connection of the plunger member, 55, to the lever, 56, for operating connection with the plunger element, 50, and the diaphragm, C, is afforded by a third plunger member, 57, telescoped within the plunger member, 55, and connected at the inner end with the lever, 56, as seen at 56^a. A leather packing, 63, is provided at the end of the bore in the plunger member, 55, in which the plunger member, 57, is telescoped for absorbing the shock of the intrust of the inner telescoped plunger member, 57, and preventing the operation from being noisy.

The plunger member, 55, is provided with a slide bearing for its thrust movement, by a bushing, 58, in the casing terminal, A¹, and said plunger member is formed with an encompassing annular recess, 59, which serves the purpose of a lubricant pocket to which lubricant from the crank case obtains access by a port, 61^b, provided in the terminal, A¹, at a point which is exposed in the crank case when the pump casing is mounted in operative position on the latter. This recess serves another purpose by the shoulder, 63, which results from reducing the plunger member in diameter to form the annular recess, 59, namely, by co-operating with stop pins, 64, 64, set into the casing terminal, A¹,

through the bushing, 58, and projecting into the annular recess, 59.

The operation of the structure as described may be understood from the foregoing description. The spring, 60, tends normally to hold the diaphragm, C, at the position shown in the drawing, which is the limit of its feeding stroke, and at that position it operates to hold the entire plunger element comprising the telescoping plunger members, 55 and 57, and the lever, 56, at the position shown in the drawing, that is, with the plunger member, 57, thrust toward the cam, 40, and thereby telescoped within the plunger member, 55. Assuming that at this position of the diaphragm the cam, 40, is at the position shown in the drawing,—at the climax of its inactive phase,—the plunger, 55, stands projecting from the terminal, a¹, of the casing member, A, to the limit of its stroke at which it is stopped by check pins, 64, 64, which are at that stage encountered by the shoulder formed by the inner end of the annular recess, 59, encompassing the plunger.

Upon the rotation of the cam from the position described the plunger member, 55, is thrust inwardly against the reaction of the spring, 52, and positively thrusts the inner telescoped plunger, 57, in the direction for rocking the lever, 56, to cause its opposite end to retract the plunger, 50, and the diaphragm, C, which thereby receives its intake stroke which, it will be observed, is a positive stroke derived directly from the cam, 40. As the cam continues its revolution from its active to its idle phase, the spring, 52, reacting on the plunger, 55, causes the latter at its outer end to follow the cam until at the end of the revolution it re-occupies the initial position shown in the drawing. During the idle phase also, the spring, 60, reacting on the diaphragm, C, gives the latter its feeding stroke and causes the inner telescoped plunger, 57, to follow the plunger, 55, in its retracted movement. This cycle of movement being repeated until the pump has supplied the carburetor, filling the fuel chamber thereof, so that, when running conditions are such that the engine requirement is only a small part of the feeding capacity of the pump, and so that upon the retraction of the diaphragm to the full limit which is caused by the positive actuation of the cam, it can make only a small portion of its feeding stroke, it will be seen that the plunger member, 57, will remain in the position to which it is forced in the active phase of the cam, while the plunger member, 55, is retracted by the spring 52, in the idle phase of the cam. And it will be seen, therefore, that there is a range of lost motion between the two plunger members, 55 and 57, which is necessary to accommodate the action of the pumping diaphragm whose feeding stroke will be varied according to the fuel requirement of the en-

gine, permitting a feeding stroke of the dia-
phragm only sufficient to replace in the car-
bureter chamber the amount of fuel taken by
the engine in the corresponding stroke of the
engine piston.

Upon considering this operation it may
be understood that the reason for interpos-
ing the lever, 56, between the two plunger
members which it connects, instead of ar-
ranging for action of the cam directly upon
the plunger member, 50, is to obtain the ad-
vantage of the positive action of the cam for
the intake or suction stroke of the pumping
member diaphragm, C, and it may be under-
stood that in taking advantage of the oppor-
tunity afforded by the interposition of the
lever, to offset the plungers connected to the
opposite ends of the lever from each other,
it is important, in view of the necessity of
keeping the fuel-accumulating chamber, D,
in a position extending downward from the
fuel intake passage which leads therefrom to
the pumping chamber, and at the same time
being able to mount the apparatus on the en-
gine crank case at the varying positions
which may be necessary in view of the vary-
ing form of the engine and crank case and
the position of the cam shaft therein, that
the construction should be, in a sense, flexi-
ble to adapt it to be accommodated to vary-
ing situations in the respects mentioned; and
for this purpose the two casing members, A
and B, are formed at their mated faces at
which they are secured together, and with
respect to the means for so securing them, so
that the casing member, A, may be rotated
about the axis of the diaphragm relatively
to the casing member, B, through any de-
sired angle, and the parts may be secured to-
gether at varying positions in the range of
such rotative adjustment without in any re-
spect affecting the operation of the parts.
And similarly, the terminal of the casing ar-
ranged for mounting against the wall of the
engine crank case is formed for rotative ad-
justment at said mounting through any de-
sired angle from the position shown, at
which the lever, 56, is shown in vertical position,
to a position at which the lever shall
be horizontal or in reversed vertical position.
The apparatus is thus adapted to be mounted
on the engine crank case with all the parts
in suitable relation to each other for their
operation, whether the lever, 56, is posi-
tioned vertically or at an oblique angle, and
whether its actuated member is the upper
or the lower, the right hand or the left hand.

Four of the different positions to which
the casing member, B, may be adjusted rela-
tively to the casing member, A, and to the en-
gine, without angular change in the position
of the casing member, A, that is, keeping
said casing member, A, unchanged in posi-
tion with respect to the parts which are re-
spectively horizontal and vertical, particu-

larly without displacing the fuel chamber,
C, from the proper position relatively to the
fuel passages, are illustrated in Figure 4,
showing said member in full line at position
I, corresponding to Figure 1, and in dotted
lines at positions II, III and IV.

And it will be seen that the possibility of
thus varying the mounting of the device on
the engine, without causing the fuel-accumu-
lating chamber to be turned to an inoperative
or undesirable position, is effected by provid-
ing for securing together the two casing mem-
bers at their mated flanges by bolts equally
spaced apart in the circumference of the
annular flanges, and employing a similar
expedient of securing the casing member to
the engine casing by a plurality of bolts dis-
tributed at equal angular intervals in the
circle in which the bolt holes are formed in
the flange of the casing terminal by which
it is secured to the engine casing. And
specifically, the variability of mounting in
order to serve the purpose indicated is practi-
cally effected by spacing the securing bolts in
both instances 45° apart, requiring therefore
eight bolt holes and bolts in each flange, the
position of the bolt holes of the circular group
in the casing member flanges which are se-
cured together, in respect to their relation to
the vertical and horizontal diameters of the
respective circular groups, being made to
correspond with the positions of the bolt holes
in the circular group of the flange of the
terminal of the casing member by means of
which it is secured to the engine and the
corresponding group of bolt holes in the en-
gine body. And it will be understood that
the employment of eight bolt holes rather
than any lesser number is for the purpose of
providing for the angular adjustment to posi-
tion the casing member, B, with its laterally
offset portions, either in vertical plane or in
horizontal plane, or inclined in either direc-
tion intermediately between vertical and
horizontal position. And it will be under-
stood that the invention with respect to this
feature is not limited to the specific means
and manner of rendering the securement and
mounting rotatively variable; but that any
means of adapting the parts to be secured
together and to the engine at a correspondingly
plurality of correspondingly angularly dif-
ferentiated positions would be within the
scope of this feature of the invention.

I claim:—

1. A pumping device for mounting on an
internal combustion engine to be operated by
an engine cam, said device comprising a cas-
ing containing a pumping chamber, a pump-
ing member mounted reciprocably therein,
said casing having a hollow extension at the
side toward which the pumping member
makes the intake stroke, and being adapted
at its outer extremity for mounting at an
aperture in an engine casing with its cavity

- registering with such aperture; a plunger mounted in the terminal portion of said extension and protruding therefrom for intruding into the engine casing through the registering aperture of the latter; a second plunger which carries the pumping member reciprocably mounted in the casing, a lever of the first class connecting said plungers for causing each to communicate to the other moving 5
- 10 ment the reverse of its own; springs reacting on said plungers respectively for thrusting them in opposite directions, said thrust of the second plunger being in fuel feeding direction of the pumping member.
- 15 2. In the construction defined in claim 1, the hollow extension of the casing having its terminal portion in which the first plunger is mounted offset laterally with respect to the part in which the second plunger is mounted.
- 20 3. In the construction defined in claim 1, the pumping chamber comprising two members having mated faces in a substantially vertical plane and having registering cavities in said mated faces and adapted to be secured together at said vertical plane, said two members being constructed and arranged with respect to the means for securing them together for permitting relative rotation of the one with respect to the other about the 25 axis of their registering cavities, the casing extension having its terminal portion formed for mounting and securement on the engine casing at varying positions of adjustment about the axis of said terminal; whereby said 30 casing member may be arranged in mounting on the engine casing with its opposite end portions offset from each other either horizontally or vertically without changing the position of the other casing member.
- 35 4. A pump device for mounting on an internal combustion engine to be operated by the engine cam comprising two casing members having mated faces in a vertical plane and registering cavities in said faces respectively and adapted to be secured together at 40 said mated faces to form by their registered cavities, a chamber for a pumping member; a pumping member operably mounted in said chamber; one of said casing members having 45 intake and discharge passages, and a fuel chamber interposed in the intake passage arranged for downward delivery of fuel thereto and upward delivery of the fuel therefrom in its course toward the pumping chamber, the other casing member comprising an 50 intermediate portion and terminal portions extending in opposite directions from said intermediate portion, and laterally offset from each other, one of said terminal portions having the vertical face and recess for mating with the first casing member, the other of 55 said terminal portions being arranged for mounting on an engine casing at an aperture thereof, said terminal portions being ar- 60 ranged for securement to the first mentioned casing member and to the engine casing respectively, adjustably about the axes of said terminal portions respectively; whereby in said mounting said terminal portions may be offset laterally from each other, either horizontally or vertically, without angular change in the position of the other casing member.
5. A pump structure for the purpose indicated having two casing members, the first comprising a pumping chamber and a liquid accumulating chamber, the second carrying the pump-operating means, said means comprising two plunger elements and movement 65 communicating means connecting said elements, the latter being respectively connected to the pumping member and protruding for actuation by actuating means, said plunger elements being laterally offset from each other, said second casing member being arranged for securement at one end to the first casing member at a plane transverse to the thrust of the first plunger, and at the other end to a fixed support at a plane transverse to the thrust of the second plunger; and means for securing said second casing member at its opposite ends arranged to afford such securement at selected positions of adjustment of said second casing member throughout an angular range of at least 70 ninety degrees.
6. A pumping device for mounting on an internal combustion engine to be operated by an engine cam comprising in combination with a reciprocable pumping member a plunger element by which said member is actuated, a second plunger element arranged to be actuated by the engine cam, the cam having an active and an idle phase in the cycle of its rotation, said two plunger elements being laterally offset from each other, a lever of the first class which connects said plunger elements, a spring reacting on the pumping member for giving it its feeding stroke, the second plunger element comprising two inter-telescoping plunger members, one of which is directly connected to said lever and the other of which is exposed to the action of the cam in the active phase thereof, and a spring reacting between said last mentioned plunger member and the casing for causing said plunger member to follow the cam in the idle phase of its cycle of rotation.
7. An apparatus for the purpose indicated having a casing member arranged to be intruded into the casing of an engine which the apparatus serves; a two-membered plunger whose members are telescoped with each other, the outer telescoped member being arranged to protrude from one end of the apparatus casing into the engine casing for co-operating with an actuating engine part,

the inner telescoping member protruding from the outer within the apparatus casing at the opposite end of said outer member from that at which it projects into the engine 5 casing, said outer telescoped plunger member being reduced in diameter intermediate its ends, forming an annular encompassing recess extending for a limited distance corresponding to the length of the plunger stroke, 10 and a stop pin set in through the apparatus casing member which intrudes into the engine casing engaging said plunger member at said annular recess, for encounter with the shoulders formed at the opposite limits of said 15 recess, for limiting the plunger stroke and preventing escape of the plunger member from the casing member.

8. The construction defined in claim 7, the apparatus casing member having at the portion 20 thereof which projects within the engine casing an aperture opening at the outer end in the engine casing cavity and at the inner end in said recess whereby access is afforded for lubricant from the engine casing to said 25 annular recess, and the latter becomes a lubricant pocket carrying lubricant for distributing the same over the slide bearing of the plunger.

9. In an apparatus for the purpose indicated 30 having a casing member arranged for intruding into the casing cavity of an engine, and a two-membered plunger whose members are telescoped one within the other, the outer telescoped plunger member reciprocating in the apparatus casing member which projects in the engine casing cavity, and having intermediate its ends a portion 35 of reduced diameter forming an annular cavity within the bearing of said plunger member in the apparatus casing member, said casing member having at a point within the engine casing cavity and within the extent of 40 said annular cavity of the plunger member an aperture affording access for lubricant from the engine casing cavity to said annular 45 cavity, and said plunger member having an aperture from said annular cavity to the slide bearing of the inner telescoped plunger member in the outer member.

50 10. An apparatus comprising a casing having a member constructed for intruding into the crank casing of an engine, and having a plunger element journaled slidingly for reciprocation in the intruded portion of the apparatus casing member, the latter having 55 a lubricant duct leading to said slide bearing from a point on the exterior of said intruded part which is exposed within the engine crank case when the apparatus casing is 60 mounted thereon, said plunger element having an annular encompassing recess forming a lubricant pocket, said lubricant duct leading to said pocket for supplying lubricant thereto for lubricating the slide bearing of 65 the plunger in the apparatus casing member.

11. An apparatus comprising a casing having a member constructed for intruding into the crank case of an engine, and having a plunger element comprising two plunger members telescoped with each other, the outer telescoped member being journaled slidingly for reciprocation in the intruded portion of the apparatus casing member, the latter having a lubricant duct leading to said slide bearing from a point on the exterior of 70 said intruded part which is exposed within the engine crank case when the apparatus casing is mounted thereon, the outer telescoped member having an aperture located for registering its outer end with said lubricant duct of the casing member at a substantial portion of the longitudinal movement 75 of the plunger in the casing member and at its inner end open for delivering lubricant to the inner telescoped member.

12. An apparatus comprising a casing having a member constructed for intruding into the crank case of an engine, and having a plunger element consisting of two plunger members telescoped one within the other, the outer telescoped member being journaled slidingly for reciprocation in the intruded portion of the apparatus casing member, the latter having a lubricant duct leading to said slide bearing from a point on the exterior of 80 said intruded part which is exposed within the engine crank case when the apparatus casing is mounted thereon, the outer telescoped member of said plunger element having an encompassing recess located, and extending 85 longitudinally thereof a distance corresponding to the stroke of the plunger, for maintaining said annular recess in registration with said lubricant duct, and having a duct leading from said encompassing recess for 90 conducting lubricant to the inner telescoped member.

In testimony whereof, I have hereunto set my hand at Chicago, Illinois, this 20th day of November, 1928.

LEONARD H. WHEELER.
